COMBUSTION APPARATUS

Martin De Lin, Holland, Mich., assignor to Holland Furnace Company, Holland, Mich., a corporation of Michigan

Application February 19, 1938, Serial No. 191,433

2 Claims. (Cl. 126—108)

This invention relates to combustion apparatus, and more particularly to a novel form of heat exchanger which includes an expansion chamber within which combustion is produced, and a horizontally extending vertically elongated economizer through which the products of combustion travel in passing from the expansion chamber to an exhaust flue.

The present application is a continuation in part of my copending application Serial No. 134,-983 filed April 5, 1937.

The primary advantage of a horizontally extending economizer is that it permits of more efficient transfer of heat to the medium to be heated. This advantage is only partly realized where the economizer itself is not uniformly heated throughout its vertical extent. Accordingly, it is a primary object of this invention to provide a horizontally extending economizer which is so constructed and arranged that the products of combustion passing therethrough are distributed substantially uniformly throughout its vertical extent. Thus, the maximum efficiency of heat transfer is obtained.

Broadly, this primary object of the invention is attained by proportioning the cross-sectional areas of the economizer and the exhaust flue with which it is associated so that the products of combustion cannot pass through the economizer without being distributed throughout its vertical extent. Specifically, this result is accomplished in either of two ways. The smallest cross-sectional area of the economizer may be the same as the effective cross-sectional area of the exhaust flue. As an alternative, the economizer may be connected to the exhaust flue by upper and lower flue outlets with means for varying the cross-sectional area of the upper outlet to provide for a balance between the effective drafts of the two outlets so that the products of combustion will be withdrawn from the economizer through both outlets in substantially equal volumes.

In order to obtain the maximum advantage of the present invention throughout a variable range of operation of the combustion apparatus, both of the foregoing arrangements may be advantageously employed in the same apparatus.

In addition to the foregoing primary object, the invention has as its objects: the provision of a novel form of heat exchanger made up of sectional compartments; the provision of novel means for securing the compartments together to form a unit; and the provision of novel means

for supporting the heat exchanger to provide for expansion and contraction thereof.

A preferred embodiment of the invention is shown in the accompanying drawings, wherein:

5 Figure 1 is a vertical sectional view of combustion apparatus embodying the present invention taken on substantially the line 1—1 of Figure 3;

10 Figure 2 is a vertical cross-sectional view of the apparatus taken on substantially the line 2—2 of Figure 1;

Figure 3 is a horizontal sectional view taken on substantially the line 3—3 of Figure 1; and

15 Figure 4 is a fragmentary view taken on the line 4—4 of Figure 2.

The apparatus illustrated in the accompanying drawings includes several major parts, namely, a supporting frame 10, a heat exchanger 11 mounted upon the supporting frame 10, an inner casing 12 enclosing the heat exchanger, an outer casing 13 enclosing the inner casing, circulating fan units 14, air filters 9, an oil burning unit 15, and an open topped primary combustion chamber 16 disposed within and spaced from the walls of heat exchanger 11. The nozzle of oil burning unit 15 discharges into the chamber 16. The heat exchanger 11, the inner casing 12 and the outer casing 13 are constructed from standard sectional elements whereby the size thereof may be readily varied. Likewise, the filters 9 and fan units 14 are of a character whereby one or more may be used.

20 The products of combustion formed in the heat exchanger 11 are discharged through flue outlets 17 and 18 extending through inner casing 12 and outer casing 13. Outer casing 13 is provided with a cold air inlet opening 19 adjacent the top thereof and immediately over the flue outlets 17 and 18. As an alternative to the use of a single air inlet opening 19, the outer casing may be provided with a plurality of smaller openings in its vertical walls as shown at 19a. Communication is provided between the interior of outer casing 13 and the interior of inner casing 12 through means of a pair of openings 20 in the bottom wall of the inner casing 12. The inner casing 12 is provided with an outlet opening 21 in its top wall for the discharge of heated air.

25 Each of the fan units 14 is operatively associated with one of the openings 20 in the bottom of inner casing 12. They are of the axially intake and radial discharge type whereby the cold air is drawn into the outer casing 13 through inlet opening 19 and then forced through inner casing 12 and out of outlet opening 21. Thus,

the air in the outer casing 13 is under a vacuum and the air in the inner casing 12 is under pressure. Consequently, there can be no loss of heat or combustion gases through outer casing 13.

As best shown in Figures 1 and 2, the fan units 14 are housed within a compartment defined by the bottom wall 12a of vertical casing 12, the vertical frame members 8, the vertical walls 6 and 7, and the removable filter units 9. Outer casing 13 is provided with openings in its side walls affording access to the filter units 9. These openings are closed by removable panels. Five filter units are shown, the two on each side of the apparatus being inclined from the vertical to expose a larger surface area to the air traveling vertically downwardly from opening 19. The direction of travel through the apparatus of the air to be heated is shown by the arrows in Figure 2. Thus, it will be seen that all of such air passes through the filters 9.

In order to control the direction of flow of the air passing from outer casing 13 into inner casing 12 through openings 20, there are associated with openings 20 adjustable vanes 30. These vanes distribute the air delivered to the inner casing 12 by the fans 14 in such manner that the air will contact the maximum area of heat exchanger 11 in passing through the inner casing 12.

The heat exchanger 11 is of novel construction. It includes an expansion chamber 11a surrounding the primary combustion chamber 16 and an economizer chamber 11b adjacent the exhaust flues 17 and 18. The entire heat exchanger 11 is made up of a plurality of sectional compartments 31 and 32 detachably connected to each other. The several sectional compartments 31 form the expansion chamber 11a and the compartments 32 form the economizer chamber 11b.

All of the compartments 31 and 32 are of generally elliptical shape in horizontal cross-section, and of substantially rectangular shape in vertical cross-section. They are all formed to provide oppositely disposed side walls of substantially greater extent than the other walls thereof.

All of the compartments 31 communicate with each other through aligned restricted openings 33 formed in the sides thereof. These openings are of such size and such character that substantial portions of the opposite side walls of each compartment 31 are directly exposed to the air which is circulated vertically through the inner casing 12 by the fans 14. As best shown in Figures 1 and 3, the openings 33 in compartments 31 provide a straight horizontal passageway for the products of combustion which is of substantially uniform height and width, the height being materially greater than the width.

Communication is provided for between the expansion chamber 11a and the economizer chamber 11b by cooperating vertically elongated openings 34 formed in the side wall of adjacent compartments 31 and 32. Communication is provided between the compartments 32 by cooperating vertically elongated openings 35 formed in the adjacent side walls thereof. Openings 34 and 35 are of the same height but of a lesser width than openings 33. The openings 34 and 35 are arranged to form a serpentine horizontally extending vertically elongated passageway through the economizer 11b.

Communication is provided between the economizer chamber 11b and the flue outlets 17 and 18 by a pair of restricted openings 36 and 37 in the adjacent side wall of the last compartment 32.

Flue outlets 17 and 18 are shown as connected to a common exhaust or chimney flue 48 of uniform cross-sectional area.

Provision is made to insure that the compartments 32 forming the economizer section 11b will be more or less uniformly heated throughout their vertical extents. This is accomplished by maintaining proper relation between the cross-sectional areas of the economizer and the exhaust flue 48, and by providing a damper 49 with which to vary the cross-sectional area of the upper flue outlet 18.

The cross-sectional area of communicating openings 35, the combined cross-sectional areas 15 of the flue outlets 17 and 18, and the cross-sectional area of exhaust flue 48 are all substantially equal. Thus, when the apparatus is operating at its maximum capacity—as when exhaust flue 48 is completely filled with the products of combustion passing therethrough—the products of combustion also necessarily completely fill the vertically elongated openings 35 in passing through the economizer. In this manner, the compartments 32 forming the economizer 11b are heated throughout their vertical extents.

Of course, when the apparatus is operating at its maximum capacity, as described above, the damper 49 associated with flue outlet 18 will be in its open—horizontal—position. If the apparatus be operated at less than its maximum capacity, damper 49 will be adjusted to vary the cross-sectional area of flue outlet 18 so as to provide for a substantially equal pressure or draft in the two outlets 17 and 18. In this manner, the products of combustion are withdrawn or expelled from the economizer in equal volumes through the two outlets, thus maintaining a relatively uniform distribution of the products of combustion throughout the vertical extent of the economizer.

The size and location of all of the openings 34, 35, 36 and 37 are such that a major portion of the side walls of the compartments 31 and 32 are directly exposed to the air circulated through inner casing 12. As best shown in Figure 3, these openings are arranged to form a serpentine passageway through the economizer portion of the heat exchanger. The air circulated through inner casing 12 passes between the convolutions of this serpentine passageway.

Each of the compartments 31 and 32 is provided with four ears 38. The ears on adjacent compartments are formed with aligned openings for the reception of securing rods 40 which together with the clamping nuts 41 at the opposite extremities thereof serve to detachably connect all of the compartments 31 and 32 together in operative relation. Coil spring elements 42 are shown as mounted upon one end of the rods 40 and interposed between the compartments 32 and the adjacent clamping nut 41. Thus, the compartments are connected to each other in a manner to permit the natural expansion and contraction resulting from the changes in temperature produced within the heat exchanger 11.

As previously stated, the heat exchanger 11 is mounted upon a supporting frame 10. The supporting frame 10 consists of two spaced apart horizontally extending parallel pipes 10b supported at their opposite ends by vertical pipes 10a. Each pair of vertical pipes 10a are connected to each other by a cross-support 10c. Thus, there is provided a rigid supporting frame for the heat exchanger 11. The front end of the heat exchanger is anchored to the support-

ing frame by saddles 5, which have an interlocking engagement with the frame and the lower edge of one of the compartments 32 (see Fig. 4). Except for the two saddles 5, the heat exchanger 11 is not connected to the supporting frame in any way, but is merely mounted upon the horizontally extending pipes 10b and held in position by gravity and the surrounding inner jacket 12. Consequently, the compartments 31 and 32 comprising the heat exchanger 11 are free to expand and contract in a horizontal direction longitudinally of the pipes 10b. The ears 38 at the top and bottom of the compartments 31 and 32 prevent horizontal movement of the heat exchanger in a lateral direction relative to the pipes 10b.

The opening 33 in the end compartment 31 (right hand side of Figures 1 and 3) is partially closed by a plate 43 provided with a large rectangular opening. A second plate or closure 44 is detachably connected to plate 43.

Closure plate 44 is insulated, as shown, and is provided with an opening through which a conduit extends. Primary combustion chamber 16 is connected to the inner end of the conduit. Burner 15 is connected to the outer end of the conduit. The plate 44, combustion chamber 16, and burner 15 comprise a unitary assembly which can be removed and installed as a unit. Burner 15 is supported by a bracket 45 carried by plate 44.

As clearly shown in Figures 1 and 3, the inner casing 12 and the outer casing 13 are provided with openings in the front end thereof which are closed by the plates 43 and 44. Of course, in this particular zone the inner casing 12 is not spaced from the heat exchanger 11, and the outer casing 13 is not spaced from the inner casing 12. Plates 43 and 44 and burner 15 are enclosed within an auxiliary housing 47.

The operation of the apparatus herein illustrated and described is as follows:

Combustion is initiated in the primary combustion chamber 16 by the oil burner 15. Combustion there initiated expands into the expansion section 11a of heat exchanger 11 and the products of combustion then pass into economizer section 11b, and finally into the exhaust flue 48 through the flue outlets 17 and 18. The expansion section provides a horizontal passageway for the products of combustion which is of substantially uniform height and width. The economizer section of the heat exchanger provides a horizontal passageway for the products of combustion which is of substantially uniform height and varying width. Adequate heating of the expansion chamber, and particularly the economizer section, throughout its vertical extent is assured at maximum operation by the relation between the effective cross-sectional areas of the passageway through the economizer and the exhaust flue 48. A similar result is attained when the apparatus is operated at less than its maximum capacity by suitable adjustment of the damper 49 associated with the upper exhaust flue 18.

Air is drawn into the outer casing 13 through the inlet opening 19 by the fans 14. In traveling between the inlet opening 19 and the fans 14 a major portion of the air either passes over the outer surface of the inner casing 12 or over the outer surface of the flue outlets 17 and 18, ab-

sorbing some heat therefrom. The fans 14 force the air from outer casing 13 into inner casing 12 through the openings 20 and out of the inner casing 12 through the outlet opening 21. In traveling through the inner casing 12 the air passes between all of the compartments 31 and 32, and is directly exposed to contact with a substantial portion of the side walls of compartments 31 and a major portion of the side walls of compartments 32. All together, six sides of the heat exchanger are directly exposed to the air passing through inner casing 12. In this manner, a very efficient transfer of heat from the heat exchanger to the air to be heated is effected. In traveling from the outer casing 13 to the inner casing 12, all of the air to be heated passes through the filters 9.

From the foregoing description it will be apparent that the present invention provides a novel form of heat exchanger from which the heat of combustion is most efficiently transferred to the medium to be heated.

While only a single embodiment of the invention has been herein shown and described, it should be understood that this invention is not limited to this single embodiment but, on the contrary, is co-extensive with the scope of the appended claims.

I claim:

1. Combustion apparatus comprising a heat exchanger and a support therefor, the support including a pair of horizontally extending parallel members, the heat exchanger being slidably mounted upon said members to permit longitudinal and lateral movement of the heat exchanger with respect to said members, means for limiting the lateral movement of said heat exchanger with respect to said members comprising a projection carried by the heat exchanger and positioned between said members, and means for fixing the longitudinal position of one end of the heat exchanger with respect to said members comprising a saddle rigidly secured to one of said members and a projection on the heat exchanger mounted in said saddle.

2. Combustion apparatus comprising a heat exchanger and a supporting frame therefor, the supporting frame including a pair of horizontally extending spaced parallel bars, the heat exchanger including a plurality of vertically disposed and horizontally aligned compartments slidably mounted upon said bars to permit longitudinal and lateral movement of the compartments with respect to said bars, each of said compartments including a plurality of projections, said projections being formed to provide aligned openings for the reception of a tie rod, a tie rod slidably mounted in said aligned openings and having clamping means at its opposite ends to resiliently clamp the compartments together, at least one of the projections on each of said compartments being located between the horizontal bars whereby to limit the lateral movement of the heat exchanger with respect to the supporting frame, and means for fixing the longitudinal position of one end of the heat exchanger with respect to the supporting frame comprising a saddle rigidly secured to one of said bars and a projection on the heat exchanger mounted in said saddle.

MARTIN DE LIN.
